COSMETIC HOLDER

Albert Hagel, Newark, N. J., assignor to Consolidated Safety Pin Company, Bloomfield, N. J., a corporation

Application October 4, 1933, Serial No. 692,059

6 Claims. (Cl. 206—56)

This invention relates to improvements in cosmetic holders, and more particularly to improvements in lipstick holders.

One object of this invention is to provide a cosmetic holder having a pivoted cover and a slidable elevator with improved means for locking the cover in closed position.

Another object of this invention is to provide a cosmetic holder having a cosmetic-supporting member with improved means for securing the cosmetic thereto.

With the above and other objects in view, this invention includes the improved features, parts and combinations of parts disclosed in the following description, appended claims and accompanying drawing forming a part of this specification.

In the accompanying drawing, in which one way of carrying out the invention is shown for illustrative purposes:

Fig. 1 is a perspective view illustrating a lipstick holder constructed in accordance with this invention;

Fig. 2 is an enlarged side elevation of the lipstick holder;

Fig. 3 is a rear elevation looking from the right of Fig. 2;

Fig. 4 is a side elevation similar to Fig. 2, the casing being in section, but with the cover in open position and with the lipstick projected from the holder;

Fig. 5 is a horizontal cross-section on the line 5—5 of Fig. 4;

Fig. 6 is a perspective view of the elevator;

Fig. 7 is a perspective view of the cover; and

Fig. 8 is a perspective view of the push-button.

Referring to the drawing, 10 is a casing of general U-shaped form in horizontal cross-section, and is provided with a bottom or end 11. Opposite sides of the casing 10, near the lower end thereof are provided with apertures 12 within which pivot the pivots 13 of the downwardly-extending portion 14 of the cover 15. The downwardly-extending portion 14 is provided with spaced side-wings 16, one of which has an actuating-cam 17 and a dwell-portion 18. The lower end of the portion 14 is bent transversely to provide a closed bottom-portion 19, and a limit-edge 20 adapted to engage against the inner rear face 21 of the casing 10 to limit the opening movement of the cover 15 as illustrated in Fig. 4. The inwardly-projecting or bulged locking-boss 22 is formed on the portion 14 between the pivots 13 and bottom-portion 19.

One side 23 of the casing 10 is provided with a

longitudinally-extending slot 24 in which is slidably mounted an elevator-operating member or push-button 25 having prongs 26 extending through said slot 24 and engaging opposite edges thereof to be guided thereby, and extending on through openings 27 in the cosmetic-supporting member or elevator 28, whereupon the extreme inner ends 29 of the prongs 26 extend inwardly and angularly downward, as shown in Fig. 3, with the result that the prongs secure the elevator firmly to the elevator-operating member or push-button 25, and at the same time, the inwardly- and downwardly-extending ends 29 provide suitable anchoring means to engage the lipstick and hold it securely within the cosmetic or lipstick chamber of the elevator 28.

It will be observed that owing to the inward and angularly-downward direction of the ends 29, when the lipstick is forced into the cosmetic chamber of the elevator 28, the lipstick flows around and underneath the ends 29, thus securely anchoring the lipstick in place.

The elevator 28 is formed with an outwardly-projecting or bulged locking-boss 30, the locking-bosses 22 and 30 being of such size and relationship that when the elevator is moved to its lower-most position, as shown in Fig. 2, the locking-boss 30 snaps past the locking-boss 22 to produce a snap-lock engagement between the bosses to lock the cover in closed position, thus minimizing the tendency of the elevator to shift its position when carried in a handbag or the like. Thus, by this snap-lock locking engagement, all the parts of the lipstick holder will remain firmly and completely locked until the elevator is moved by a person intentionally sliding the push-button 25 to release the snap-lock engagement, thus effectively protecting the contents of the handbag against soiling from the lipstick holder, and at the same time preventing contamination of the lipstick holder with dust or dirt.

In operation, assuming the lipstick holder to be in closed position as illustrated in Fig. 2, by pushing upward on the push-button 25, the boss 30 will be released from its snap-lock engagement with the boss 22, whereupon, as the push-button 25 is slid upwardly along the slot 24, the upper prong 26 engages the actuating cam-surface 17, and swings the cover to open position as shown in Fig. 4, with the limit-edge 20 in engagement with the inner rear surface 21 of the casing 10. Further movement upward of the push-button 25 causes the lipstick 31 to be projected outwardly beyond the upper end of the casing. The lipstick

may be projected to any desired extent and at all times the prongs 26 ride along the dwell-portion 18 of the adjacent wing 16, thus cooperating with the parts 20, 21 to securely and definitely hold the cover in open position.

When it is desired to retract the lipstick 31, the push-button 25 is slid downwardly until the lower part of the elevator 28 engages the lower portion of the extension 14, whereupon the cover 10 15 is swung toward closed position, and as the boss 30 snaps past the boss 22, the cover 15 is quickly closed and securely but yieldably locked in closed position by the snap-lock engagement between the bosses 22 and 30.

15 The invention may be carried out in other specific ways than that herein set forth without departing from the spirit and essential characteristics of the invention, and the present embodiment is therefore to be considered in all respects 20 as illustrative and not restrictive, and all changes coming within the meaning and equivalency range of the appended claims are intended to be embraced therein.

I claim:

25 1. A cosmetic holder comprising: an elongated casing having an opening at its upper end; a cover for said opening having an extension extending lengthwise of, and pivoted intermediate its ends to, said casing; an elevator in the casing and 30 slidable longitudinally thereof; and interengageable projections on the cover and elevator adapted to have snap-lock engagement to lock the cover in closed position.

35 2. A cosmetic holder comprising: an elongated casing having an opening at its upper end; a cover for said opening having an extension extending lengthwise of, and pivoted intermediate its ends to, said casing; an elevator in the casing and 40 slidable longitudinally thereof; and interengageable projecting bosses on the cover and elevator

adapted to have snap-lock engagement to lock the cover in closed position.

3. A cosmetic holder comprising: an elongated casing having an opening at its upper end and a side wall provided with a longitudinal slot; a cover for said opening having an extension extending lengthwise of, and pivoted intermediate its ends to, said casing; an elevator in the casing and slidable longitudinally thereof and including an operating portion extending outwardly through said slot; and interengageable projecting bosses on the cover and elevator adapted to have snap-lock engagement to lock the cover in closed position. 80 85

4. A cosmetic holder comprising: a casing; a cosmetic-supporting member in the casing and provided with a cosmetic chamber, and prong-means extending inwardly and angularly downward into the cosmetic chamber through and angularly away from, a wall of said cosmetic chamber. 90

5. A cosmetic holder comprising: an elongated casing having a side wall provided with a longitudinal slot; an elevator in the casing and slidable longitudinally thereof and provided with a cosmetic chamber; and an operating-member slidably mounted in said slot and having prong means extending inwardly and angularly downward into the cosmetic chamber through and angularly away from, a wall of said cosmetic chamber. 95 100

6. A cosmetic holder comprising: an elongated casing having a side wall provided with a longitudinal slot; an elevator in the casing and slidable longitudinally thereof and provided with a cosmetic chamber; and an operating-member having a pair of superimposed, spaced apart prongs extending through said slot and inwardly and angularly downward into the cosmetic chamber through and angularly away from, a wall of said cosmetic chamber. 105 110 115
